UNITED STATES PATENT OFFICE.

HENRY CRADDOCK, OF RENSSELAER, NEW YORK, ASSIGNOR TO TOWNSEND FURNACE & MACHINE SHOP CO. INC., OF ALBANY, NEW YORK, A DOMESTIC CORPORATION.

GRATE LOCK.

Application filed June 29, 1922, Serial No. 571,693. Renewed May 12, 1926.

My invention relates to an improvement in grate locks.

This lock is used in connection with a receiving-basin, such as commonly employed 5 in streets, the lock being designed to prevent the grate from being opened by the unauthorized, and, furthermore, to prevent vehicles and horses from tipping or sliding it out of place, thereby affording safety in 10 driving over the same, and protecting the municipality from law-suits.

In the accompanying drawings:

Fig. 1 is a plan view;

Fig. 2 is a vertical section on the line 15 A—B of Fig. 1;

Fig. 3 is a section on the line C—D of Fig. 1;

Fig. 4 is a bottom plan view of the lock frame;

20 Figs. 5 and 6 are plan and side elevations respectively of the bolt;

Figs. 7 and 8 are plan and side views of the cam;

Fig. 9 is a view of the key employed for 25 locking and unlocking the grate.

The numeral 1 represents the frame, preferably made of cast-iron having a base flange 2 at the bottom, and an annular internal shoulder 3 at the top, the inner surface 4 of which slopes to the inner wall 5 of the frame.

The grate 6 is adapted to rest upon the annular shoulder 3, as shown in Fig. 2.

A lock frame 6' is cast on the lower surface of the grate, and the bolt 7 is slidably mounted in this lock frame, it being confined at the edges as shown in Fig. 1, so that its movement is necessarily limited to a radial inner and outer slide.

40 To this end, it is provided with a central slot 8 of the peculiar form shown in Figs. 1 and 5. Within this slot the cam 9 is located. This cam has a cylindrical hub 10 at the bottom, which fits and turns in a correspondingly-shaped recess 11; and when the cam is turned, the bolt is slid by the engagement of the cam against one of the parallel sides of the slot 8.

When the cam is turned to the position 50 shown in Fig. 2, the bolt rests against the slope 4 just below the annular shoulder 3 of the frame, in that way holding the grate rigidly in position.

The bolt has a key-hole 12 at the center 55 adapted to receive the end of the key 13,

which latter is lowered through the hole 14 in alignment therewith in the grate. This hole 14 is formed with a slightly less diameter at the surface, as shown in Figs. 2 and 3, so that any stones or hard substances getting inside will pass the lock frame and not interfere with the working parts cored on the inside of the lock frame.

To assemble the lock, the cam is placed in the slot 8 of the bolt, at right-angles to the 60 position shown in the drawings, whereupon the bolt and cam are slid into place in the lock frame. A groove 15 is formed to receive, and form clearance for, the two up-standing lugs 16 on the cam, and when the 65 bolt and cam have been pushed far enough into place, so that the hub 10 drops into the recess 11, the lugs drop, leaving the groove, as shown for instance in Fig. 2, thus making it possible to rotate the cam freely.

The key is made of round iron, with a ring 17 forged thereon, and has a projection 18 to limit its insertion through the opening 14, the ring acting as a stop, and bringing the projection 18 on the key in line with 75 the recess 19 in the key-hole 12.

The opposite end of the key is forged back into the form of a handle 20. By reversing the key until the projection 18 is out of registry with the recess 19, the handle can be 80 used for removing the grate.

To lock the grate, the key is inserted into the cam and turned until the cam has moved the bolt forward, as indicated in Figs. 1 and 2, so that it is pressed securely against the 90 side slope 4 of the side wall 5 of the basin frame, thus preventing the grate from being lifted out. To unlock, the movements are reversed.

To remove the bolt and cam, two fingers 95 may be inserted in the cam from beneath the lug, pushing the cam up until the hub 10 is out of the recess 11, whereupon the cam is turned to its original position or until the lugs are in line with the groove 15 in the 100 grate, when the cam and bolt are slid out in the opposite direction from which they are moved when inserted.

I claim:

1. The combination of a lock-frame having a longitudinal groove formed therein, a bolt slidably connected with the lock frame and having a slot formed therein, a cam arranged to turn in the slot, said cam having upstanding lugs slidable through the 110

longitudinal groove when the bolt and cam are being inserted into position within the lock frame.

2. The combination with a basin frame, 5 of a grate having a lock-frame, a bolt slidably connected with the lock frame and having a slot formed therein, a cam arranged to turn in the slot, said cam having upstanding lugs and the grate having a longitudinal groove therethrough for receiving the lugs when the bolt and cam are inserted in place within the lock frame.
- 10 3. The combination with a basin frame, of a grate having a lock-frame cast integral

therewith and cored out, a bolt slidably connected with the lock-frame and having a slot formed therein, a cam having a key-hole therethrough, the cam constructed and arranged to turn in the slot, the cam having a cylindrical hub and the lock frame a recess to receive the hub, the cam having upstanding lugs and the grate having a corresponding groove through which the lugs pass when the bolt and cam are inserted in place within the lock frame. 15 20 25

In testimony whereof I affix my signature.

HENRY CRADDOCK.
